UNITED STATES PATENT OFFICE

ALBERT H. TINNERMAN, OF CLEVELAND, OHIO

THERMOSTATIC CONTROL FOR STOVE OVENS

Application filed May 5, 1928. Serial No. 275,315.

This invention relates to gas ranges and is particularly concerned with the mounting of thermostatic controls for regulating oven temperatures. Heretofore, the practice with 5 one type of control has been to mount a regulator on the side of the oven adjacent the front corner thereof, where it is unsightly and difficult to keep clean. In addition, the thermostat used with this type of regulator 10 extends from side to side of the oven where only one heat zone of the oven is in contact therewith. It is more desirable to extend the thermostat from front to rear, where it is subjected to the average of heat zones, since 15 the rear portion of the oven is usually hotter than the front portion.

When the thermostatic device extends from front to rear, then it is necessary to utilize a controlling member or regulator which is 20 disposed on the front part of the oven. Such arrangement is illustrated in Letters Patent of the United States No. 1,578,939, which were issued to me March 30th, 1926. In such patent, the door frame has an opening through 25 which access may be had to the controlling member by means of a key. Some difficulty is apt to be experienced in this type of installation, particularly if the door opening does not exactly register with the control member; 30 and in addition, the user is apt to find it inconvenient if the key should be lost.

A further objection to this arrangement is the fact that the dial must be fastened onto the door frame. Such doors usually embody 35 an enameled surface, and hence there is danger of cracking the enamel when the dials are applied thereto.

An object of the present invention is to utilize a thermostat which extends from the 40 front to the rear of an oven, and at the same time to make a controlling member which can be readily operated from the front of the oven without requiring the dial to be fastened onto an enameled surface, and without necessitating the removal of the key to permit opening 45 of the door.

In the drawings, I have shown one form of 50 my invention in Fig. 1, which embodies a vertical section through the oven of a gas range, and shows a thermostat extending from

the front to the rear; Fig. 2 is a front elevation of part of the oven; Fig. 3 is a front elevation of part of the oven, showing a modified form of my invention, and Fig. 4 is a vertical section taken through the oven on a 55 plane indicated by the line 4-4 in Fig. 3.

Referring now to Fig. 1, 10 designates an oven of a gas range having a thermostat 11 mounted therein, and extending from the front to the rear of the oven. The details of 60 construction of the thermostat, as illustrated in this figure, are shown in my Patent No. 1,578,939, heretofore referred to, and hence, for the present purpose, it will only be necessary to state that the thermostat embodies an 65 adjustable regulating member 15, which projects through an opening in the oven front frame member 16, and has a key 17 disposed outside the door 18, and that the door has an opening 19 of sufficient size to permit opening 70 thereof, without requiring the key to be removed. Directly behind the key, I have shown a dial 20 which is mounted on a lug 21. This lug forms part of the frame and is of such size as to provide a satisfactory bearing 75 for the rotatable member 15. The dial, as shown, is substantially flush with the outer surface of the door frame, and hence is readily visible and available for use.

In Fig. 3, instead of cutting an opening 80 through the door frame, I have shown such frame as having a recess 25 adjacent the corner portion, and as having the dial substantially flush with the oven front frame. This is shown more in detail in Fig. 4, wherein the 85 dial is illustrated at 20^a, and the oven front frame is indicated at 16^a. Thus the dial and key lie substantially within the continuation of lines, which define the marginal edges of the top and side edges of the door.

An important advantage of my invention, as is evident from the description and illustration in the drawings, is the fact that the thermostatic controlling or regulating member may be mounted adjacent the front of the 90 oven and may be readily adjusted by means of a key which is attached permanently thereto. The dial being flush with the oven front frame or door is relatively inconspicuous, and yet is accessible for enabling adjustments 95 100

to be quickly made. In addition, the dial may be easily attached, without endangering the appearance of the enameled surfaces.

I claim:

- 5 In a stove, the combination with an oven structure having a front frame member and a door, a thermostatic control device mounted within the oven, and having an operating portion thereof projecting through the frame member, a dial mounted on the member, a key associated with said operating portion, and positioned in front of the dial outside the oven, said door having an opening sufficient to clear the dial and key when the door is opened.
- 10
- 15

In testimony whereof, I hereunto affix my signature.

ALBERT H. TINNERMAN.
